UNITED STATES PATENT OFFICE.

GEORGE HALL, OF DETROIT, MICHIGAN, ASSIGNOR TO NELSON, BAKER & COMPANY, OF DETROIT, MICHIGAN, A CORPORATION OF MICHIGAN.

DESIGN FOR A SIFTER-TOP CAN OR SIMILAR RECEPTACLE.

56,427.

Specification for Design.

Patented Oct. 26, 1920.

Application filed February 27, 1919. Serial No. 279,607. Term of patent 14 years.

To all whom it may concern:

Be it known that I, GEORGE HALL, a citizen of the United States of America, residing at Detroit, Wayne county, Michigan, have invented a certain new, original, and ornamental Design for a Sifter-Top Can or Similar Receptacle, shown in the accompanying drawing, forming a part of this application, in which—

Figure 1 is a front view of a sifter top can or similar receptacle, showing my new design; Fig. 2 is a side elevation thereof; and Fig. 3 is a top plan view.

What I claim is:

The ornamental design for a sifter top can or similar receptacle, substantially as shown.

(Signed)

GEORGE HALL.
